UNITED STATES PATENT OFFICE.

CLIFTON CHISHOLM, OF CLEVELAND, OHIO, ASSIGNOR TO THE AMERICAN MULTIGRAPH COMPANY, OF CLEVELAND, OHIO, A CORPORATION OF OHIO.

REMOVABLE INSERT FOR PRINTING FORMS.

Application filed July 11, 1924. Serial No. 725,369.

REISSUED

To all whom it may concern:

Be it known that I, CLIFTON CHISHOLM, a citizen of the United States, residing at Cleveland, in the county of Cuyahoga and 5 State of Ohio, have invented a certain new and useful Improvement in a Removable Insert for Printing Forms, of which the following is a full, clear, and exact description, reference being had to the accompanying drawings.

The object of this invention is to provide a simple and inexpensive device for holding a few lines of printing members, adapted for ready mounting in a printing machine. The invention is particularly useful 15 where many impressions are taken from a form, a minor portion of which is changed from time to time.

A more particular use of this invention is 20 in connection with a multigraph having a rotary drum on which are mounted rows of type. My removable insert is adapted for ready mounting on such railed drum and adds to the type form a few lines adapted 25 to printing in conjunction therewith, but readily changed without disturbing the type on the drum.

The invention hereinafter is more fully explained in connection with the drawings 30 and the essential novel characteristics are summarized in the claims.

In the drawings Fig. 1 is an end elevation, partly broken away, of a multigraph drum, equipped with rows of individual type and 35 my removable insert: Fig. 2 is a fragmentary plan of such drum so equipped: Fig. 3 is a cross section through the removable insert device: Fig. 4 is a perspective of the holder member of the removable insert, which is 40 directly mounted on the drum: Fig. 5 is a perspective of the lock for the holder.

In Figs. 1 and 2, A indicates a multigraph drum having about its periphery parallel rails *a* with overhanging edges. B indicates 45 short type grooved on its opposite sides and adapted to be slid endwise of the rails into the space between them, such type being retained in place by the overhanging heads of the rails, and, if desired, prevented from 50 laterally shifting by stop plugs or clips, C (Fig. 2) mounted in the channels.

The parts described constitute usual multigraph equipment with which my removable insert is designed to cooperate.

My removable insert comprises a holder 55 adapted for ready mounting on the drum, a plate with upwardly extending projections mounted on the holder, and embossed printing strips mounted on the plate. These parts have such thickness and are so formed 60 that the face of the printing characters on the embossed strip is the same radial distance from the axis of the drum as the face of the type B.

The holder for the removable insert, designated 10, comprises a plate having on its underside means for holding it on the drum and on its upperside means for holding the plate which carries the strips. As shown in Figs. 3 and 4, the holder plate 10 has on its 70 underside longitudinal rails 11 which are of inverted T-shape in cross section. These rails may be welded or otherwise secured to the plate 10. This plate has its edges curled under upwardly and inwardly to provide the hooked flanges 12. Such a holder may be readily mounted on the multigraph drum by being slid lengthwise thereof, the rails 11 being so positioned on the plate 10 that they register with channels between some of 80 the rails *a* on the drum.

The plate which is mounted on the holder and carries the embossed strips is designated 20. This plate has parallel rows of 85 upwardly projecting buttons 21 stamped up from the plate and connected with it in direction of the row, but disconnected at the edges, which project freely toward adjacent rows. Such a plate is shown, described, and claimed in the patent to W. J. Deming, 90 #1,438,584 issued Dec. 12, 1922, to The American Multigraph Company. In addition to the stamped up buttons, the plate preferably has also upstanding corrugations 95 22 between the buttons, which act to stiffen the plate and with the buttons provide a continuous support for the embossed strips. This feature is covered in Patent #1,438, 582 of B. J. Craig, issued Dec. 12, 1922 to The American Multigraph Company.

The embossed strips are designated 30 in Figs. 1, 2, and 3. Each strip is a metal member having printing characters on it embossed upwardly from the underside of the strip. The edges of the strip are curled or flanged downwardly and inwardly as shown in 31. Such an embossed strip may be slid endwise over the row of buttons and 100 105

be retained thereon by reason of the flanges on the strip underhanging the arcuate projecting edges of the buttons.

Simple means may be employed to prevent the embossed strips shifting longitudinally on the plate 20. This may be affected by the simple expedient of making an inward dent by prick punch on some blank space on the strip. If desired, I may form an abutment for these strips at one end by inserting a flat flexible strip of metal transversely of the rows through the space beneath aligned buttons. Such a button strip is shown at 23 in Fig. 2 and is claimed in my co-pending application #673,418, filed Nov. 8, 1923.

It will be seen that the embossed strips, made by some suitable machine, may be quickly mounted and secured on the plate 20. Likewise, such plate with the strips may be quickly mounted in the holder 10 and the holder 10 may be quickly mounted on the multigraph drum.

If desired, the holder may be prevented from shifting laterally on the drum by the use of the usual plugs or clips such as shown at C for locking the type lines. However, I regarded it preferable to provide a special lock on the holder 10. I have shown such lock in the form of a screw 40, the shank of which passes through a hole in the holder, and a nut 41 threaded thereon and occupying one of the channels of the drum and prevented from rotating by engagement with the side walls of adjacent rails of the drum. Such screw is so located in the plate 10 that the nut aligns with one of the channels when the rails 11 aligns with other channels and such holder is slid into place on the drum, when the screw is turned by a screw driver, the holder becomes clamped to the drum. The head of the screw performs another function, forming an abutment for the plate 20. Accordingly, by properly positioning the holder on the drum, the plate, shoved lengthwise against the screw head comes into the proper position to have the embossed strips held by the positioning strip 23 in proper registration with the rest of the form on the drum.

I have found it usually sufficient to lock the holder in position and use the head of the screw 40 as an abutment for the plate, the latter fitting the overhanging edges 12 of the holder with sufficient snugness so that it does not become displaced in operation of the machine. However, if desired, a suitable clip may be inserted in one of the channels at the other end of the holder and bear against that end of the plate and thus positively prevent its shifting in that direction.

It will be noted that the removable insert as described is adapted for mounting on a railed member whether the latter be a rotary drum or a flat bed. If the device is

used on a flat bed the holder plate 10 is made flat and both rails 11 have their webs vertical. When the holder is intended for mounting on a drum the plate 10 is preferably curved concentrically of the drum surface and the rails 11 are positioned radially thereon, as shown in Figs. 3 and 4.

It will be seen that the same plate 20 may be used over and over again with different embossed lines thereon. The ordinary equipment for this attachment may well comprise one holder 10, several plates 20 and the requisite embossed lines, these embossed lines to be made up according to the different matter to be inserted and mounted on different plates 20, when the body of the form is on the drum and the holder locked in place in proper position with relation thereto, one plate 20 with its embossed strips may be slid into place in the holder and the desired number of copies run off, the machine stopped, and the plate 20 with its strips slid out and another plate with strips substituted. The plates and strips occupy a small space and may be stored in assembled condition for subsequent use, or the embossed strips may be removed and others mounted on the plate, according to the nature of the printing operation.

Having thus described my invention, I claim:

1. The combination of a holder having a downwardly extending holding device whereby it may be mounted in a printing machine and an upwardly extending retaining device, a plate adapted to be mounted on the holder by means of said retaining device, and embossed printing strips mounted on said plate.

2. The combination of a holder having downwardly extended means for holding it on a printing machine and an upwardly extending retaining device, a plate adapted to be mounted on the holder by means of said retaining device and having upwardly extending overhanging projections, and printing strips mounted on said projections.

3. The combination of a holder having on its underside a pair of downwardly projecting underhanging members, whereby the holder may be mounted and retained on a member having parallel rails with underhanging edges, a plate, means for holding such plate on the holder, and printing members mounted on the plate.

4. A holder having a pair of parallel rails upon its underside with projecting edges, and having means on its upperside for holding a plate in combination with such plate and embossed printing strips mounted on the plate.

5. A combination of a holder having laterally projecting members on its underside to hold it on a railed member, the edges of said holder being flanged upwardly and in-

wardly, a plate on the holder retained by said flanges, and printing members mounted on the plate.

6. The combination of a holder comprising a plate having on its underside two parallel rails with ledges adjacent their bottoms, said plate having its edges curled upwardly and inwardly, a plate mounted on the upperside of the holder and having its edges embraced by curled edges, the last mentioned plate having upwardly extending overhanging projections, and embossed printing strips having inwardly flanged edges overlying said projections and held thereon.

7. The combination with a member having parallel rails with overhanging edges, of a holder mounted thereon, and having two portions projecting from its underside extending into the space between pairs of adjacent rails, a plate mounted on the holder, and printing members mounted on the plate.

8. The combination, with a member having parallel rails with overhanging edges, of a holder mounted thereon, and having two portions projecting from its underside extending into the space between pairs of adjacent rails, a plate mounted on the holder and having upwardly extending projections, and embossed printing slips mounted on the plate by means of said projections.

9. The combination with a drum having parallel radial rails with overhanging edges, a holder comprising a curved plate, mounted on the rails and held thereto by means extending into channels between rails, a plate mounted on the holder, and printing members mounted on the plate.

10. The combination with a drum having parallel radial rails with overhanging edges, a holder having on its underside underhanging rails adapted to slide longitudinally into channels between pairs of adjacent rails on the drum, said holder having means for retaining a plate thereon, a plate so mounted on the holder, said plate having upwardly projections and embossed printing strips mounted on said plate.

11. The combination with a portion of the printing mechanism, of a holder adapted to be slid into place thereon, a lock carried by the holder and engaging the printing machine to prevent the shifting of the holder, a plate mounted on the holder, and printing strips mounted on the plate.

12. A holder comprising a plate having on its underside downwardly and laterally projecting members adapted to enter a channel of a printing machine provided with overhanging rails, a screw and nut couple mounted on the holder, one member of which may occupy a channel between rails and be held from rotation thereby, the other of which is accessible above the holder, a plate mounted on the holder, and printing members mounted on the plate.

13. The combination of a holder having means for mounting it on a railed member of a printing machine, a screw and nut couple mounted on the holder, one member of which may occupy a channel between rails and be held from rotation thereby and the other of which is accessible above the holder, a plate mounted on the holder and abutting the top member of said couple, and printing members mounted on the plate.

14. The combination of a holder having on its underside a pair of parallel rails with projecting ledges, the edges of the holder being curled inwardly at the top, said holder being adapted to be slid into position on the railed member of a printing machine with said ledges underhanging the edges of the rails, a screw projecting through the holder and located so as to engage a channel between rails when the downward members on the holder occupy other channels, a nut on the screw adapted to occupy one of the channels, and be held thereby against rotation, a plate mounted on the holder with its edges embraced by said flanges and its end adapted to abut the head of the screw, and embossed strips mounted on the plate.

In testimony whereof, I hereunto affix my signature.

CLIFTON CHISHOLM.
